UNITED STATES PATENT OFFICE.

PAUL PIGNOT, OF HASTINGS, ASSIGNOR TO THE ALEX. SMITH & SONS CARPET COMPANY, OF YONKERS, NEW YORK.

DESIGN FOR A CARPET.

SPECIFICATION forming part of Design No. 20,273, dated November 4, 1890.

Application filed October 10, 1890. Serial No. 367,638. Term of patent 3½ years.

To all whom it may concern:

Be it known that I, PAUL PIGNOT, a citizen of the United States, residing at Hastings, Westchester county, New York, have invented 5 a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design consists of a body A and a border B. The body A is composed of groups of large conventionalized leaf and flower forms surrounded by branches and leaves and all lying 20 on a shaded groundwork of leaf and flower

forms. The border B is composed of an inner margin of grass-like ornamentation, a middle portion of flower and leaf forms surrounded by branches and leaves and all lying on a shaded groundwork of leaf and flower forms, 25 and an outer margin of shaded leaf and grass-like forms.

What I claim as new, and desire to secure by Letters Patent, is—

1. The design for carpets, consisting of the 30 body A, substantially as shown.
2. The design for carpets, consisting of the border B, substantially as shown.
3. The design for carpets, consisting of the body A and the border B, substantially as 35 shown.

PAUL PIGNOT.

Witnesses.
